UNITED STATES PATENT OFFICE.

LEROY BROWN, OF WAITSBURG, WASHINGTON TERRITORY.

SULKY-PLOW.

SPECIFICATION forming part of Letters Patent No. 249,890, dated November 22, 1881.

Application filed April 16, 1881. (Model.)

To all whom it may concern:

Be it known that I, LEROY BROWN, of Waitsburg, in the county of Walla Walla, and Territory of Washington, have invented a new and 5 useful Improvement in Sulky-Plows, of which the following is a specification.

Figure 1 is a plan view of my improvement. Fig. 2 is a side elevation of the same, the near wheel being removed. Fig. 3 is a plan view 10 of the adjacent ends of the bars that support the tongue. Fig. 4 is a front elevation and a plan view of the plate to which the tongue is pivoted. Fig. 5 is a front elevation of the upper part of the lever and its attachments for 15 controlling the tongue. Fig. 6 is a bottom view of the plow. Fig. 7 is a sectional side elevation of the plow. Fig. 8 is an elevation of the land-side part of the rotary-colter standard. Fig. 9 is an elevation of the plowed-land part 20 of the rotary-colter standard. Fig. 10 is a front elevation of the rotary colter and its standard. Fig. 11 is an end elevation of the rotary-colter hub.

The object of this invention is to improve the 25 construction of the sulky-plows for which Letters Patent Nos. 211,696 and 226,705 were granted to me January 28, 1879, and April 20, 1880, respectively, in such a manner that they will be more substantial, and can be more conveniently guided, controlled, and adjusted.

A are the wheels, and B is the axle, of the carriage. To the axle B, at the inner side of the off wheel A, is secured a casting or coupling-block, C, to the rabbeted outer side of the 35 rear end of which is secured by bolts or rivets the lower end of a bar, D. The bar D extends upward vertically to about the level of the top of the wheel A, and is then bent forward at right angles. At the forward side of the wheel 40 A the bar D is bent at right angles inward, forward, and again inward, forming a recess or offset.

To the lower side of the coupling-block C is secured by bolts or rivets the rear part of a 45 bar, E, which extends forward, and at the forward side of the wheel A is bent upward at right angles, so that its upper end will overlap the bar D at its first inward bend.

To the axle B, at its inner side of the near 50 wheel A, is secured a casting or coupling-block,

F, to the lower side of which is secured by bolts or rivets the rear part of a bar, G. The bar G projects forward, and at the forward side of the wheel A is bent inward at right angles, and is curved upward and inclined inward to the level 55 of the forward part of the bar D, and then extends horizontally along the end of the said bar D to a point opposite the horizontal part of the body of the bar D, and is then bent to the rearward at right angles, so that its end will overlap the body of the bar D at its first inward bend. The ends of the bars E G are secured to the bar D by bolts or rivets, and the end of the bar D is secured to the bar G by bolts or rivets, as shown in Fig. 3, thus forming a 60 firm support for the tongue H.

Upon the box or frame formed by the end parts of the bars D E G is placed a plate, I, upon the ends of which are formed lugs J to rest against the sides of the bent end parts of 70 the bars D G. The lugs J project below the lower edges of the bars D G, and are perforated to receive the bolt or pin K, by which the plate I is secured in place, and which rests in notches in the lower edges of the said bars 75 D G. The tongue H rests upon the plate I, and is pivoted to it by a vertical bolt, L, passing through the said plate and tongue, as shown in Figs. 1 and 2. The rear part of the tongue H passes back nearly to the forward 80 bend of the bar D, and to the lower side of its said rear part is secured, by bolts or rivets, a flat bar, M, which rests upon the horizontal part of the bar D, and its rear end passes through and projects beyond a horizontal guide 85 or keeper, N, attached to the bar D at its angle. The keeper N holds the rear end of the tongue H down to its place and limits the lateral movements of the said tongue H. The rear end of the bar E projects a little beyond 90 the rear end of the coupling-block C, and has a pivot formed upon it to receive the lower end of the lever O, which passes up across the rear edge of the keeper N, and is held against the said keeper by a spring, P, attached to the 95 end of the bar E and pressing against the said lever O.

To the lever O is pivoted a catch, Q, the shoulder of which engages with the rear end of the tongue-bar M, so that the said tongue 100

can be adjusted to regulate the line of draft and cause the plow to take or leave land, as desired. The forward end of the pivoted catch Q is beveled, so that it will engage with the 5 end of the tongue-bar M automatically, and is held down upon the said tongue-bar by a spring, R, attached to the lever O, or to an arm, S, or other support attached to the said lever. The outer end, T, of the arm S is bent 10 downward, or has a downwardly-projecting arm attached to it, to serve as a stop to prevent the engaging end of the catch Q from dropping down so low that it will not engage with the end of the tongue-bar M when the 15 said end is swung against it.

To the upper side of the rear edge of the keeper N is attached, or upon it is formed, a catch-bar, U, with the teeth of which engages the lower end of the spring-pawl V. With 20 this construction the lever O and the tongue H M can be adjusted to cause the plow to take or leave land, as required, and the tongue can be left free to vibrate in turning. The rear end of the bar G projects in the rear of the 25 coupling-block F, and to it is hinged the end of a bar, Z, which is bent laterally, passes across the rear end of the machine at a rearward inclination, passes around the rear side of the off wheel, passes forward parallel with 30 the said wheel, and is bent inward around the forward part of the wheel.

The forward end of the bar Z is pivoted to the crank-arm of the bent lever a. The middle part or body of the lever a is placed parallel with the axle B, and works in bearings attached to the horizontal parts of the bars E G. The inner arm of the bent lever a projects inward and upward into such a position that it can be conveniently reached and operated 40 by the plowman from his seat. The bent lever a is secured by a ratchet-plate, b, and a spring-pawl.

To the rear side of the lower part of the mold-board j are attached, or upon it are formed, 45 lugs p, which lugs p may be a projecting end of the lug l and arm m or frog of the plow. The lugs p interlock with the lugs q formed upon the rear part of the share n, so as to hold the rear edge of the share n against the forward edge of the mold-board j and hold the 50 said share from lateral movement.

The share n is held from forward movement by the rod r, the forward end of which is hooked into a hole in the rear end of the inner 55 lug, q, or in a separate lug attached to the said share. The rear end of the rod r passes through a lug, s, secured to the rear upper part of the bar i, and has a nut screwed upon

the said rear end. With this construction the share n will be drawn tightly into place by 60 tightening the nut of the rod r, and can be quickly detached by loosening the said nut.

t is the rotary colter, the hub u of which is made long to give it a long bearing upon its axle, preventing a rapid wear, and causing it 65 to wear true. The hub u is provided with an axle-box, v, of anti-friction metal, to cause it to work easier and wear longer. The axle of the rotary colter t is attached to the lower ends of the two bars w, that form the standard. The 70 bars w pass up upon the opposite sides of the colter t, and at a point a little above the top of the said colter have inward offsets formed upon them, so that their upper parts may rest against each other. The upper part of the 75 standard w is secured to the plow-beam g and bar Z by a clamp, which may be one of the clamps that secure the beam g to the bar Z, or a separate clamp, as may be desired or convenient. The upper parts of the bars w are secured to each other by a bolt, x, which passes through a hole in one of the said bars and a slot in the other bar, as shown in Figs. 8, 9, and 10, and has a nut screwed upon its forward end. By this construction, by loosening the bolt x the bars w can be moved upon each other to adjust the colter t exactly in the line of draft and equalize the bearing on its axle, so that it will work easy and true and without any undue strain upon its axle or standard. 80

y is the driver's seat, which is attached to the upper end of the standard z. The lower end of the standard z is secured by a bolt, 1, to the rear of the coupling-block 2, attached to the axle B. 90

Having thus described my invention, I claim as new and desire to secure by Letters Patent—

1. In a sulky-plow, the combination, with the bent bar D, the tongue H, and the lever O, of the keeper N, the spring-catch Q R, and the ratchet and pawl U V, substantially as herein shown and described, whereby the tongue can be readily adjusted, securely held, and conveniently released, as set forth. 95

2. In a sulky-plow, the combination, with the rotary colter t and the plow-beam g, of the standard formed of two bars, w, secured to each other by a bolt, x, passing through a hole in the one bar and a slot in the other, substantially as herein shown and described, whereby the said colter can be readily adjusted into line with the draft, as set forth. 100

LEROY BROWN.
